(57) **CLAIM**

The ornamental design for a gaming terminal, as shown and described.

DESCRIPTION

FIG. 1 is a front perspective view of a gaming terminal showing our new design;

FIG. 2 is a front view thereof;

FIG. 3 is a right side view thereof;

FIG. 4 is a left side view thereof; and,

FIG. 5 is a top view thereof.

The broken line showing of the remainder of the gaming terminal illustrates environmental structure and forms no part of the claimed design.
